UNITED STATES PATENT OFFICE.

LAMBERT VON REIS, OF HERZOGENRATH, GERMANY.

PROCESS OF GRINDING AND POLISHING GLASS PLATES.

Application filed July 14, 1925. Serial No. 43,572.

To all whom it may concern:

Be it known that I, LAMBERT VON REIS, a citizen of Germany, residing at Herzogenrath, No. 25 Merksteinerstrasse, State of Prussia, Germany, have invented certain new and useful Improvements in a Process of Grinding and Polishing Glass Plates, for which an application was filed in Germany Aug. 15, 1923; and I do hereby declare the following to be a full, clear, and exact description of the invention, such as will enable others skilled in the art to which it appertains to make and use the same.

In the known dressing of rough glass plates by submitting them to the successive operations of coarse grinding or smoothing, second grinding and polishing by passing, for instance, a plurality of tables carrying the glass plates beneath a series of grinding and polishing appliances arranged in succession to one another, interruptions of the treatment are unavoidable in the polishing operation, because the felts of the polishers have to be interchanged or cleaned by washing from time to time. Therefore, while the grinding appliances may continue their operation uninterruptedly, the polishing appliances must be stopped temporarily for the purpose of washing or interchanging the felts.

The invention has for its object to avoid this disadvantage and to provide a process for grinding and polishing glass plates which is practically continuous. According to the invention, the polishing appliances are caused to travel in the direction in which the glass is fed, so that in the course of the process a vacant space is produced between the appliances for second grinding and the polishing appliances; into this vacant space is either placed a reserve polishing appliance or the foremost one of the polishing appliances in use after same has been lifted from the glass and its felts interchanged or washed, so that the same number of polishing appliances is always operating on the glass. Besides, it is possible to lift every single polishing appliance out of the series of appliances if necessary, such as in case an appliance requires repair, and to place in the space thus produced another polishing appliance, e. g., a reserve appliance.

In order to allow of the invention to be more readily understood it will now be de-

scribed with reference to the accompanying drawings in which:

Fig. 1 is a diagrammatic side elevation of a plant for the smoothing, second grinding and polishing of glass plates, at the beginning of the operation,

Fig. 2 is a similar elevation illustrating the formation of a vacant space between the appliances for second grinding and the polishing appliances,

Fig. 3 is a corresponding elevation illustrating the insertion of the foremost polishing appliance into the vacant space,

Fig. 4 is a vertical transverse section through the polishing portion of a plant designed to carry out the present process, and

Fig. 5 is a side elevation of this portion of the plant.

Referring first to Figs. 1 to 3, the numeral 1 designates the row of tables supporting the glass plates and moving in the direction of the arrow α , 2 are the successively arranged smoothing appliances, 3 are the appliances for second grinding and 4 are the polishing appliances. The grinding appliances 2 and 3 execute their working movements without changing their positions, while the polishing appliances are caused to travel in the direction in which the glass is fed as shown in Fig. 2, so that in the course of the process a vacant space is produced at A between the foremost one of the appliances 3 for second grinding and the rearmost one of the polishing appliances 4. Upon this space having become sufficiently large, the foremost polishing appliance (see Fig. 3) is lifted from the glass, its felts are interchanged or cleaned and the appliance is carried over the succeeding polishing appliances in a direction opposite to the feed movement of the glass and then lowered into the space A so that it may immediately take part again in the polishing of the glass. As the lifting of the appliance, the interchanging or cleaning of the felts and the transport of the same into the new position is executed very rapidly, the continuous treatment of the glass is not subjected to any interruption worth consideration.

According to the polishing portion, shown in Figs. 4 and 5, of the plant for carrying out the process, the table 1 supporting the glass plates (not shown) is adapted to slide on rails 5 and has imparted to it a linear movement by means of a gear 6

through a shaft 7 and a pinion 8 which is in engagement with a rack bar 9 fastened to the underside of the table 1. Arranged above the table 1 are four polishing appliances 4 comprising each three polishing tools 4'. These tools are mounted in supports 10 which are adapted to travel on slides 11 and provided with rack bars 12 which are in engagement with pinions 13 fixed on the shaft 7. The supports 10 with the tools 4' are thus caused to travel in the direction of the feed of the glass.

Arranged to travel above the polishing appliances 4 is a lifting device 14. When the foremost polishing appliance has terminated its operation on the glass, it is lifted from the glass by means of the lifting device 14, as shown in Fig. 5, its felts are interchanged or cleaned by washing and it is then carried by the device 14 over the succeeding polishing appliances, whereupon it is lowered into operative position in the vacant space A between the rearmost polishing appliance and the appliances for second grinding.

The linear movement of the polishing appliances preferably takes place with the same speed as the feed movement of the glass plates.

As stated above there may be carried and lowered into the vacant space A by means of the lifting device 14 a reserve polishing appliance in case the foremost one of the polishing appliances 4 has to be placed out of service for any reason.

Besides, any of the polishing appliances 4 may be lifted from the glass for repair.

and replaced by a reserve appliance without disturbing the continuity of the process.

Having thus described my invention, what I claim and desire to secure by Letters-Patent is:

1. The process of grinding and polishing glass plates passing beneath a series of grinding and polishing appliances arranged in succession to one another, which consists in imparting to the polishing appliances a movement in the direction of the feed of the glass so as to cause a vacant space to be at intervals formed between the foremost grinding appliance and the rearmost polishing appliance and inserting a polishing appliance with clean felts into the said vacant space, for the purpose of avoiding an interruption of the polishing operation.

2. The process of grinding and polishing glass plates passing beneath a series of grinding and polishing appliances arranged in succession to one another, which consists in imparting to the polishing appliances a movement in the direction of the feed of the glass so as to cause a vacant space to be at intervals formed between the foremost grinding appliance and the rearmost polishing appliance, lifting the foremost polishing appliance from the glass, providing it with clean felts, carrying it rearwards over the succeeding polishing appliances and lowering it into operative position in the said vacant space so as to prevent any interruption of the polishing operation.

In testimony whereof I have signed my name to this specification.

LAMBERT von REIS.
